FILM SHREDDER HAVING OSCILLATING GUIDE NOZZLE FOR TWISTING WEB DURING FEED

Allen P. Jones and William M. Watts, Fredericksburg, and Joseph A. Zitz, Stafford, Va., assignors to American Viscose Corporation, Philadelphia, Pa., a corporation of Delaware

Application December 6, 1956, Serial No. 626,724

2 Claims. (Cl. 241—301)

The present invention relates to an apparatus for producing shredded material such as packing material from a supply of flexible sheet material. In particular, the invention relates to an apparatus for producing shredded packing material from cellophane sheets.

There is a terrific demand on the market for shredded packing material for use in packing articles and especially for protectively packing articles of a fragile nature. Many packers prefer to use a cellophane shredded packing material because of the more attractive properties of the film over ordinary paper packing material. These properties mentioned above relate to the transparency of the film, the sheen of the film, and, in some cases, the attractive colors when the shredded material is produced from colored cellophane. In producing the shredded cellophane, extremely cumbersome and unsatisfactory slitters and shredders have been used. The sheet material must be slit into narrow continuous lengths and then cut in a transverse direction to produce the shredded material of satisfactory small length.

It is therefore one object of our invention to provide a novel and improved apparatus for producing shredded material from flexible sheet material wherein the longitudinal slitting and transverse cutting of the material is accomplished in a single operation.

Another object of our invention is to provide a novel and improved method for producing shredded material from flexible sheet material.

Other objects and advantages of our invention will become apparent from a study of the following description and drawing wherein:

Figure 1 is a top view of our shredding apparatus;

Figure 2 is a side view of our shredding apparatus;

Figure 3 is a fragmentary view which shows one operating feature of our apparatus; and

Figure 4 represents a single strip of the shredded material.

Generally, our invention includes an elongated guide nozzle through which the film or sheet material is drawn in unfolded form. The film or sheet material travels downwardly through the nozzle from which it is received by a pair of cooperating slitting rolls. The nozzle is supported on a rotatable base connected with a drive means which operates to oscillate the base and the nozzle supported thereon. This oscillating action, of course, puts a slight twist into the film at a point immediately adjacent the nip of the slitting rolls whereby small minute folds will be set up in the material at the roll nip all across the material. With this arrangement, the slitting or cutting rolls will both slit the film material longitudinally and cut the material transversely to provide shredded strips of substantially uniform lengths.

Referring now to the drawing, there is provided a housing H consisting of the side walls 1, 1 and end walls 3, 3. A top plate 5 (Figure 2) is secured to the top surfaces of the side walls 1, 1 to extend across the top of the housing. An opening 7 is provided through the top plate 5.

2

Affixed to the top plate 5 is a permanent ring-shaped member 9 which, as seen in Figure 2 of the drawing, has a shoulder 11 extending around its inner periphery. Positioned concentrically within the ring-shaped member 5 is a disc 13 which has a skirt 15 depending therefrom. The skirt 15 has a shoulder 17 cut into its outer periphery. A ring-shaped bearing assembly 19 is supported between the ring-shaped member 9 and the disc 13 by the complementary shoulders 11 and 17 of these two members. To hold the disc member 13 in position to properly support the bearing assembly 19, a second or intermediate disc 21 is secured to the top of the disc 13 in fact-to-face relationship therewith. The disc 21 is of larger diameter than the aggregate diameters of the lower disc 13 and the ring-shaped bearing assembly 19 so that it extends beyond and rests upon the ring-shaped bearing assembly 19 which in turn is supported as mentioned above by the shoulders 11 and 17 of the permanent ring-shaped member 9 and the disc 13. With this arrangement, the discs 13 and 21 are rotatable as a unit within the ring-shaped base 9.

Supported in spaced-apart relationship above the intermediate disc 21 is an upper disc 23 which is secured to the disc 21 through connector studs 25, 26.

As seen further in Figures 1 and 2, each of the discs 13, 21 and 23 has an elongated slot cut out through their central portion. These slots 28 are in alignment with one another to accommodate the elongated guide nozzle 30 which extends through the slots 28 and is secured to the top disc 23. The nozzle 30 tapers inwardly as it extends downwardly toward the nozzle mouth so that the sheet material 32 passing through the nozzle may be satisfactorily guided in a desired direction as it leaves the nozzle. The mouth of the nozzle extends through the opening 7 in the top plate 5 of the housing and terminates at a point within the housing interior.

The film or sheet material 32 is passed or drawn between a pair of cooperating slitter or cutting rolls 40, 42. As seen better in Figure 3, the roll 42 has a plurality of cutting or slitting blades 44 extending around its periphery in a direction perpendicular to the axis of the roll. The rolls 40 and 42 are supported on shafts 46 and 48 and as seen in Figure 1 are driven through shaft 46 of roll 40 by the drive pulley 50. The rolls 40 and 42 therefore serve both to slit or cut the sheet material as well as to draw the sheet material from its supply source (not shown) and through the nozzle 30.

An air cylinder assembly generally designated as A on the drawing serves to urge the rolls 40 and 42 together into cutting relationship. With this arrangement, the rolls are progressively urged together as the blades wear down after prolonged cutting. The rolls may be separated for repair, etc., by merely shutting off the air supply to the cylinder assembly A.

As shown in Figure 2 of the drawing, the cut material is discharged from the housing H through a chute 55.

As explained above, our apparatus or shredder is designed to both slit or score cut the sheet material 32 as well as to cut the material transversely of its length to provide shredded strips of smaller and substantially uniform length. To satisfactorily carry out this dual operation, an oscillating drive means is provided to oscillate the guide nozzle 30 in a horizontal plane as the sheet material 32 is drawn through the nozzle. With this arrangement, the film material 32 will periodically have small folds introduced into the sheet material across the width of the material at a point immediately adjacent the nip of the cutting rolls 40 and 42. Since the sheet material is periodically folded over upon itself in this manner, the slitting cutter blades 44 cut the material in both a longitudinal direction and in a somewhat transverse direction to provide small strips which are of substan-

tially uniform length. The twist imparted to the material imparts a desired curl to the final strips.

To oscillate the guide nozzle which, as explained before, is supported in a rotatable mounting, a thrust bearing 57 (see Figure 2) is positioned over the spacing stud 26 which connects the top disc 23 with the intermediate disc 21. Affixed to the thrust bearing 57 is a drive rod 59 which has approximately a 45° bend adjacent the attached end of the rod. At one end of the housing H, there is provided a plate 60 which terminates in a triangular shaped portion which provides a bearing seat for a vertically disposed rotary drive shaft 62. Affixed to the upper end of the shaft 62 is a circular shaped table top support 64 which rotates with the drive shaft 62. Pivotal mounted on the table top support 64 adjacent the periphery thereof is a sleeve 66 through which the drive rod 59 is slidably positioned and which rotates with the table top. At the extreme end of the free end of the rod 59 there is affixed a stop or limiting collar 68 which prevents the rod from passing entirely out of the sleeve 66 as the sleeve moves to the position as shown in full dotted lines of Figure 1 during rotation of the table top 64. A similar stop collar 70 is affixed to the drive rod 59 at a point between the sleeve 66 and the attached end of the rod. This collar 70 limits the forward movement of the rod 59. Since the slide sleeve 66 is pivotally mounted to the table top support 64, the forward end of the sleeve will always approximately face the guide nozzle 30 during rotation of the table top support 64.

The full dotted line representation of the drive rod 59 in Figure 1 represents the position assumed by the rod after the table top support has traveled 180° in the direction of the arrow. During the initial phase of this rotation, the sleeve 66 is drawn along the length of the rod 59 until it abuts the stop collar 68. During the remainder of the 180° rotation, the sleeve 66 is forced against the stop collar 68 to exert a pulling force along the rod and the stud 26 to rotate the guide nozzle and its supporting structure approximately 150°.

As the table top support 64 continues to rotate in the direction of the arrow, the guide nozzle 30 and its supporting structure will travel in a reverse path instead of continuing to rotate in the direction of its initial travel during the 180° turn of the table top support 64. During this second phase of rotation, the sleeve 66 will slide back along the rod 59 until it abuts the stop collar 70 at which point, as rotation of the table top support 64 continues, it will exert a pushing force against the collar 70 and along the rod 59 to rotate the guide nozzle 30 and its supporting structure back along its previously traveled path until the guide nozzle assumes its original position as set before the first phase of rotation was initiated. The 45° angle in the rod causes the guide to return along its original path rather than to continue in its original direction of rotation. The range of travel or oscillation of the guide nozzle will be approximately 150°. As the table top support 64 continues to rotate, the oscillation path assumed by the guide nozzle and described above will be repeated. As mentioned above, this will cause the sheet material to fold upon itself at numerous points across the width of the sheet material

immediately adjacent the nip of the slitter or shredding rolls 42 and 40.

The final product is shown in Figure 4 which sets forth one strip 75 of the shredded material. Because of the periodic twist incorporated in the film or sheet material during the slitting, the shredded strip 75 tapers inwardly as it progresses toward each end of the strip. In addition to providing shredded strips of substantially uniform length, it is seen that a unique strip shape is also imparted to the shredded strips.

While preferred embodiments have been shown and described, it is to be understood that changes and variations may be made without departing from the spirit and scope of the present invention as defined in the appended claims.

We claim:

1. Apparatus for slitting continuous sheet material longitudinally and cutting it transversely comprising a slitting roller having a plurality of circumferentially extending blades, a smooth faced roller cooperating with said slitting roller, means urging said slitting roller against said smooth faced roller so as to form a nip therebetween, means for driving said rollers, a guide constructed and arranged to closely confine the edges and faces of the sheet, and means for oscillating said guide about the longitudinal axis thereof to an extent sufficient to fold the sheet upon itself and to unfold the sheet, said guide comprising means for guiding the sheet in folded and unfolded condition between said rollers whereby the sheet is cut from edge to edge by said blades and cooperating roller as it passes between said rollers.

2. In a machine for severing a continuous wide sheet into a plurality of discontinuous narrow strips, a cutting roller having a plurality of circumferentially extending axially spaced blades, a smooth faced roller mounted for cooperative engagement with said cutting roller, means urging said rollers into engagement with their axes parallel to one another so as to form a sheet feeding and cutting nip therebetween, means for driving said rollers, a guide for directing a continuous sheet into the nip of said rollers, said guide comprising a tapered sheet confining member the exit end of which is located close to the nip of said rollers, said guide being so mounted that the exit end of the sheet confining member is normally in a plane which includes the nip of said rollers, and means for oscillating said guide about the longitudinal axis of the tapered sheet confining member to an extent sufficient to fold the sheet upon itself and to unfold the sheet between said sheet confining member and said rollers whereby the edges of the sheet are presented to the blades of said cutting roller and the sheet is cut from edge to edge as it passes between said rollers.
